(57) **CLAIM**

We claim the ornamental design for a connector backshell, as shown and described.

DESCRIPTION

FIG. 1 is an isometric view of a first embodiment of a connector backshell.

FIG. 2 is another isometric view thereof.

FIG. 3 is a bottom isometric view thereof.

FIG. 4 is another bottom isometric view thereof.

FIG. 5 is a top view thereof.

FIG. 6 is a bottom view thereof.

FIG. 7 is a front view thereof.

FIG. 8 is a rear view thereof.

FIG. 9 is a right side view thereof.

FIG. 10 is a left side view thereof.

FIG. 11 is an isometric sectional view thereof taken from line 11-11 in FIG. 10.

FIG. 12 is an isometric sectional view thereof taken from line 12-12 in FIG. 9.

FIG. 13 is an isometric view of a second embodiment of a connector backshell.

FIG. 14 is another isometric view thereof.

FIG. 15 is a bottom isometric view thereof.

FIG. 16 is another bottom isometric view thereof.

FIG. 17 is a top view thereof.

FIG. 18 is a bottom thereof.

FIG. 19 is a front view thereof.

FIG. 20 is a rear view thereof.

FIG. 21 is a right side view thereof.

FIG. 22 is a left side view thereof.

FIG. 23 is an isometric sectional view thereof taken from line 23-23 in FIG. 22.

FIG. 24 is an isometric sectional view thereof taken from line 24-24 in FIG. 21.

FIG. 25 shows the first embodiment of the connector backshell in a state of use; and,

(Continued)

FIG. 26 shows the second embodiment of the connector backshell in a state of use.

The short dashed lines in the drawings depict portions of the connector back shell that form no part of the claimed design. The broken lines in FIGS. 25 and 26 that show an extension of the article depict environment that forms no part of the claimed design. The heavy dash-dot-dash lines on the article itself depict the bounds of the claimed design. The heavy dash-dot-dash lines in FIGS. 9, 10, 21, and 22 depict the cut lines of the sectional views. The very fine solid lines depict 3-dimensional contours of the connector back shell and are not intended to be construed as visible seams or edges. The heavier solid lines depict edges of the article. The stippling in the drawing shows the contour of the design.
